UNITED STATES PATENT OFFICE.

EDGAR RUSTIN, OF ATLANTA, GEORGIA.

FILE.

No. 926,829.

Specification of Letters Patent.

Patented July 6, 1909.

Application filed October 21, 1908. Serial No. 458,756.

To all whom it may concern:

Be it known that I, EDGAR RUSTIN, a citizen of the United States, and a resident of Atlanta, in the county of Fulton and State of Georgia, have invented new and useful Improvements in Files, of which the following is a full, clear, and exact description.

My invention relates to files, and especially for use in department stores, for filing sales 10 checks.

It is the present custom in department stores to file the sales checks all together on stick files, it requiring a number of girls each morning to arrange in order the sales checks 15 of each salesman, according to their numbers.

The considerable expense of having these sales checks sorted will be saved by the use of my invention, for by its use the wrapping girls or cashier can sort the sales checks as 20 they are received, so that the sales checks received from each salesman will at all times be filed by themselves in the order in which they have been received. In using my file, it is possible for the wrapping girl or cashier 25 to file the sales check by one movement of one hand, and there is no danger of the sales checks being blown away by electric fans, while being filed, or subsequently.

Still other objects of the invention will appear in the following complete description.

In this specification I will describe the preferred form of my invention, but it will be understood that I do not limit myself thereto as I consider myself entitled to all forms and 35 embodiments of the invention which may be held to fall within the scope of the appended claims.

Reference is to be had to the accompanying drawings, forming a part of this specification, in which similar characters of reference indicate corresponding parts in both the figures, in which—

Figure 1 is a perspective view of the file; and Fig. 2 is a transverse sectional view 45 thereof.

By referring to the drawings, it will be seen that standards 1 are provided, these standards being held in place by a rear member or wall 2, it being possible to make the 50 standards with the members 2 in such form as may be best suited for the particular purpose to which the file is to be put. Secured to the inner sides of the standards 1 are side members 3, the side members 3 having their 55 portions which are secured to the standards 1, disposed horizontally, but which have

projecting portions 4 which are disposed obliquely with reference to the standards 1, and to their horizontal portions. Integral with the upper terminals of the obliquely disposed portions 4 of the side members 3 are inwardly disposed flanges 5. The flanges 5 at either side of the file are disposed parallel with each other. Springs 6 are secured to the side members 3 and secured to these 65 springs 6 are bottom and rear members 7 and 8 respectively, the bottom and rear members being integral and being disposed substantially at right-angles to each other. The bottom member 7 projects forwardly 70 beyond the flanges 5 and the spring 6 is adapted to hold the bottom member 7 yielding upward so that it will press against the bottom of the flanges. Each of the bottom members 7 is constructed in the same manner, with a rear member 8 and a spring 6 to hold it upwardly, and the bottom members are disposed one over the other so that one will be in engagement with each pair of parallelly disposed flanges 5. 80

In using my invention, the operator may take one of the sales checks 9 in her left hand and by placing it in the proper division of the file, she may press the sales check 9 downwardly, thereby pressing the bottom member 7 downwardly so that the sides of the sales check will be disposed beneath the flanges 5 and by releasing her hand the bottom member 7 will be forced upwardly by means of the spring 6 thereby holding the sales 90 check 9 between the bottom member 7 and the flanges 5, so that there is no danger of its being lost or blown away.

Having thus described my invention, I claim as new and desire to secure by Letters 95 Patent:

1. In a file, standards, side members secured thereto, inwardly disposed flanges secured to the side members, a bottom member, and means to hold the bottom member 100 yielding upwardly against the flanges.

2. In a file, standards, side members secured to the standards, inwardly disposed flanges secured to the side members, bottom and rear members which are secured together substantially at right-angles to each other, and means to hold the bottom member 105 yielding upwardly against the flanges.

3. In a file, two standards, means to keep the standards at a predetermined distance 110 from each other, parallel series of side members secured to the standards, inwardly dis-

posed flanges secured to each of the side members, bottom and rear members which are secured together respectively substantially at right-angles to each other, and 5 springs secured to the side members, which support the bottom and rear members respectively and hold the former yieldingly upward against the flanges respectively.

In testimony whereof I have signed my name to this specification in the presence of 10 two subscribing witnesses.

EDGAR RUSTIN.
